CLAIM

The ornamental design for a serving platter system for grill to table convenience, as shown and described.

DESCRIPTION

This U.S. Design Patent Application is related to and hereby incorporates by reference U.S. Utility patent application Ser. No. 16/237,436, filed Dec. 31, 2018, now U.S. Pat. No. 10,413,105, issued on Sep. 17, 2019, titled “Serving Platter System For Grill to Table Convenience,” which hereby is incorporated by reference herein in its entirety including all references cited therein.

FIG. 1 is a perspective view of a serving platter system for grill to table convenience comprising a platter and a cutting board showing the new design.

FIG. 2 is a partial cross-sectional view taken through line 2-2 of FIG. 5.

FIG. 3 is an exploded top perspective view thereof with the platter and the cutting board separated.

FIG. 4 is an exploded bottom perspective view thereof with the platter and the cutting board separated.

FIG. 5 is a top view thereof.

FIG. 6 is a bottom view thereof.

FIG. 7 is an exploded side view thereof with the platter and the cutting board separated.

FIG. 8 is an exploded end view thereof with the platter and the cutting board separated.

FIG. 9 is a top perspective view of the cutting board separated.

FIG. 10 is a top perspective view of the platter separated.

FIG. 11 is a bottom perspective view of the cutting board separated.

FIG. 12 is a bottom perspective view of the platter separated.

FIG. 13 is a top view of the cutting board separated.

FIG. 14 is a top view of the platter separated.

FIG. 15 is a bottom view of the cutting board separated.

FIG. 16 is a bottom view of the platter separated.

FIG. 17 is a side view of the cutting board separated.

FIG. 18 is a side view thereof.

FIG. 19 is an end view of the cutting board separated; and,

FIG. 20 is an end view thereof.
